his atty.

UNITED STATES PATENT OFFICE.

CHARLES A. BROWN, OF LINCOLN, GRUNDY COUNTY, IOWA.

DRAFT-EQUALIZER.

SPECIFICATION forming part of Letters Patent No. 350,288, dated October 5, 1886.

Application filed June 11, 1886. Serial No. 204,887. (No model.)

To all whom it may concern:

Be it known that I, CHARLES A. BROWN, a citizen of the United States, residing at Lincoln, in the county of Grundy and State of Iowa, have invented certain new and useful Improvements in Draft Equalizers or Eveners; and I do hereby declare the following to be a full, clear, and exact description of the invention, such as will enable others skilled in the art to which it appertains to make and use the same.

Figure 1 is a plan view of a draft-evener embodying my invention. Fig. 2 is a detail elevation of the same.

15 My invention relates to draft equalizers or eveners.

The object of my improvement is to provide an evener device adapted more particularly for use in driving four or five horses abreast.

20 The invention consists in the following construction and arrangements, which will be first fully described, and the points of novelty then set forth in the claim.

1 and 2 are two bars arranged at an angle 25 to each other and pivoted together at 3.

4 is a rock-lever pivoted at 5 to the bar 2.

6 is a rigid rod pivoted to the short arm of lever 4 in one of a series of holes, 8 8'. 7 is a rigid rod pivoted to the long arm of lever 4.

30 The other end of rod 6 is pivoted at 15 to the bar 1, and the other end of rod 7 is pivoted at 22 to the whiffletree 10. 11 is a rigid rod pivoted also at 22 at one end and (at 21) at the other to bar 1. The lever 4 in this case is of 35 triangular form.

To the whiffletree 10 is secured the single-trees 12 and 13 in the ordinary manner.

14 is a whiffletree pivoted to the outer left-hand end of bar 1. To its shorter end is pivoted the whiffletree 16, to which in turn is attached the usual single-trees, 17 and 18. To the longer end of 14 is pivoted the single-tree 19.

When the draft-evener is arranged for five horses abreast, the rod 6 is pivoted at the hole 8; as shown; but when it is arranged for four horses the rod 6 is pivoted at 8' to compensate for changed arrangement of the draft.

The evener is pivoted to the carriage or wagon by the bolt 5.

It will be seen that the whiffletree 10 is not pivoted to bar 1 directly, but is pivoted to the rods 7 and 11, the latter of which is pivoted to the bar 1.

What I claim is—

The combination, with a system of equalizing-whiffletrees, of the front and rear levers, 1 and 4, the rods 6 and 7, pivoted thereto, as described, and the rod 11, pivoted at its outer end to the rod 7 and whiffletree 10, and at its inner end to the lever 1 at a point intermediate of the pivots 3 and 15, substantially as set forth.

In testimony whereof I hereto affix my signature in presence of two witnesses.

CHARLES A. BROWN.

Witnesses:

J. J. TOLERTON,
C. C. KNAPP.
